UNITED STATES PATENT OFFICE.

JOHN P. WEIS, OF NYACK, NEW YORK, ASSIGNOR TO LUCIUS N. LITTAUER, OF GLOVERSVILLE, NEW YORK.

LOOPER MECHANISM FOR SEWING-MACHINES.

1,221,253.

Specification of Letters Patent.

Patented Apr. 3, 1917.

Application filed July 13, 1915. Serial No. 39,535.

To all whom it may concern:

Be it known that I, JOHN P. WEIS, a citizen of the United States, residing at Nyack, in the county of Rockland and State of New York, have invented certain new and useful Improvements in Looper Mechanism for Sewing-Machines, of which the following is a specification.

This invention relates to sewing machines, more particularly to the looper mechanism thereof, the object of the invention being to provide an improved looper mechanism which is simple, durable and positively actuated, and which may be located entirely below the cloth plate and derive all its movements from the main rotary shaft and yet occupy as small space as possible, thereby to permit various attachments to be employed in and around the stitching position, while having such mechanism at all times accessible for threading, adjusting, lubricating, etc., one of the objects of the present improvement being to provide improved means for actuating the loopers in transverse directions or in paths at right angles to each other.

The present improvements are especially well adapted to machines having a top and bottom rotary shaft, although they may be employed to advantage in machines of the needle lever type.

In the drawings accompanying and forming part of this specification, Figure 1 is a front view showing this improved looper mechanism; Fig. 2 is an end, partly sectional, view on the line 2—2 of Fig. 1, looking in the direction of the arrow; Fig. 3 is a top plan view of Fig. 1; Fig. 4 is a partly sectional, enlarged view of the looper actuating mechanism taken on the line 4—4 of Fig. 1, looking in the direction of the arrow; Fig. 5 is a detail perspective view of this improved looper mechanism; Fig. 6 is a detail sectional view of the looper slide, showing the means for adjusting the width of the slide slightly so as to compensate for wear; Fig. 7 is a perspective view of the looper vibrating eccentric and its assembled parts; Fig. 8 is another detail of the looper vibrating eccentric and block; Fig. 9 is a detail showing a triangular cam for vibrating the loopers to give an intermittent movement or dwell to the loopers as they are passing in the rear and front of the needles; Figs. 10 and 11 illustrate different forms of loopers that may be used with this looper

operating mechanism; and Fig. 12 illustrates the feed mechanism.

Similar characters of reference indicate corresponding parts in the different figures of the drawings.

Referring to the drawings, the base plate 1 of the sewing machine carries the top arm, a portion 2 of which only is shown in dotted lines, Fig. 1, and this ordinarily carries the power transmitting means from the bottom shaft to the top shaft or vice versa. The base is provided with suitable bearings 3, 4 and 5 for the main shaft 6. The forward bearing 5 terminates in an upstanding portion 7 providing a rest for the cloth plate 8, while the extended portion 9 of the top arm 2 provides a rest for the other end 10 of the cloth plate. This cloth plate has the usual throat plate 11 and suitable slide plate, (not shown), which may be removed for the purpose of threading the loopers, etc. The main shaft 6 carries a suitable feed actuating means for actuating suitable feed dogs, the whole designated in a general way by 12, see Fig. 12. The feed lift eccentric 13 carried by the main shaft adjacent to the forward bearing 5 has a flange 14, which is drilled to receive a pin 15 carried by an eccentric cam 16 for the purpose of driving the feed lift eccentric. A block 17 fits over the eccentric 16 and operates between the flange 14 of the feed lift eccentric 13 and the flange 18 of the looper vibrating eccentric or cam, which is secured to the shaft 6 by suitable screws. This block 17 operates between the walls 19 of the fork 20 carried by a slide 21, which has beveled edges 22 to fit a corresponding groove 23 milled across the base 1 and which slide thus consists of a dovetail slide plate or block for supporting the loopers. By supporting the loopers on a slide plate a larger bearing to support the loopers and greater stability in the support thereof is obtained and lost motion more effectively overcome. Not only this, but by providing a slide plate for the support of the loopers it is practicable to provide this same slide plate directly with the fork for the reception of the eccentric carried by the main driving shaft 6 for the reciprocation of such slide plate. In other words, by providing a slide plate for supporting the loopers it is practicable to directly connect this slide plate with the driving shaft through the eccentric and thus do away with the necessity of providing intermediate connec-

tions between the eccentric and the looper supporting means, usually in the form of a looper shaft. Thus by the provision of a slide plate for supporting the loopers I am able to obtain a direct connection between the slide plate and the driving shaft, because the slide plate is of sufficient size and capacity to directly carry the fork which co-operates with the eccentric on the driving shaft and thus, as stated, do away with all intermediate connecting means between such eccentric and the slide. The foregoing direct connection, however, would not be practical in the organization shown unless the main driving shaft extended lengthwise of the machine and the looper supporting slide transversely thereof. Each end of the slide is slotted through a portion of its length, as at 24, and drilled to receive adjusting screws 25, which are provided with a reduced portion 26 and a conical end 27 which fits a corresponding seat 28 at the inner end of the slot, thereby to expand a part of the slide for the purpose of taking up wear and restoring the fit between the groove and its slide. This slide 21 is provided with a pair of hubs 29 drilled to receive conical studs 30 adjustably secured therein in any suitable manner for pivotally supporting the looper carrier 31, provided with an upstanding flattened portion 32 tapped to receive screws 33 on the front and rear faces thereof. These screws adjustably clamp the loopers 34, provided with elongated slots 35 so located as to permit adjustment of the loopers one with respect to the other, thereby to position the ends of these loopers to properly co-operate with the needles 36, which in this type of machine are so adjusted that one is set lower than the other according to the space between the needles; that is to say, when the needles are set a quarter of an inch apart the ends of the loopers are set a similar distance one from the other so that the point of each looper would meet its respective needle at the same time when making twin needle stitches. As the various classes of work this type of machine is called upon to produce require the needles being set oblique, one slightly behind the other and at the same height, it frequently occurs that the right or the left needle must be in front to suit the conditions and character of work, which makes it a difficult matter to provide loopers of different shapes to meet these conditions. Heretofore looper carriers were drilled to receive the looper shanks and the spacing of the holes represented the spacing of the needles, and when necessary to change the needle gage or the position of the needles it was necessary to substitute other parts to suit the conditions. This is entirely overcome by the present improvements, as each looper is so constructed as to meet the ex-

treme variations within the range that this type of stitching mechanism will permit, by adjusting the loopers one with respect to the other to suit the conditions and position of the needles as the case may be. The looper carrier 31 is provided with a hub 37 and is slotted as at 38 for the seating of the bottom of the front looper. This hub is tapped to receive the shoulder screw 39 pivotally carried by the end 40 of the adjustable right and left screw threaded connecting rod 41, provided with the usual lock nuts 42 to maintain its adjustment. A split ball joint 43 operates on a ball stud 44 carried by a hub 45 which is provided with a ball race groove 46 and a beveled driving gear 47. This gear meshes with and is driven by a similar gear 48 secured to the main shaft 6, which has integral therewith a triangular cam 50 hereinafter described. A casting 51 is secured to the machine base by screws 52, and the upstanding part thereof, see Figs. 1 and 4, is internally threaded, as at 53, to receive an adjustable ball race ring 54 having apertures 55 to receive a wrench for adjusting the same. The companion ball race ring 56 is identical with the ring 54 and confines the balls 57 in the groove 46 to properly position and control the gear 47 and the hub 45 and direct the ball stud 44 in its rotary movement. This construction constitutes a right angle driving means for reciprocating the looper positively to and fro across the path of the feed and permits of the highest speed without heating, noise or undue wear and affords a simple means of adjustment for taking up wear, etc. This adjustment is maintained by the clamping screw 60, see Fig. 1, which is tapped into the casting 51, a saw cut 62 permitting the rim 63 of the casting to clamp the ball race rings by reason of the screw 60. The position of the gear 47 to and from the gear 48 may be regulated by adjusting the ball race rings 54 and 56, and by drawing the rings together the ball bearings 59 will be forced down nearer the bottom of the grooves 46 of the hub 45 so that it will turn freely and without shake.

In order that the looper mechanism may perform its functions properly, improved means for handling the looper thread must be provided for in this type of machine so that sufficient thread or threads will be drawn from the supply for each stitch, as well as means for clamping the thread while it is drawn and means for taking up the slack of the thread as the loopers are leaving the needle loops and while the looper threads are clamped. I accomplish this by means of an eccentric 64 on the shaft 6 operating in a strap 65, the other end 66 of which has a bearing on a conical stud 67 clamped in an arm 68 secured to a rock shaft 69 operating in a bearing 70 carried

by the casting 51. A thread pull-off finger 71 is adjustably secured to the shaft 69 and operates between an arm 72 and a thread guide 73. A thread take-up finger 74 is secured to the other end of the shaft 69 adjacent to the bearing 70 and coöperates with the looper thread passing between the arms 75 of the thread leader 76 which is secured to an upright 77 by screws 78 under the thread clamp spring 79, (see Fig. 4). A nipper plate 80 has projections 81 and 82 located on each side of the clamp spring 79 in staggered relation to control the threads as they pass between the two and the clamp spring. The plate 80 extends back and is adjustably secured to the arm 84 of the clamping rocker, which has a hub 85 journaled on the shaft 69 between the bearing 70 and the arm 68 and the end 86 thereof terminates in an arm overhanging and co-operating with the triangular cam 50, and the bottom thereof carries two flat leaf springs to coat with the cam 50 as a fork to give positive movement to the thread clamp 80 as the main shaft itself rotates. In its operation the timing of the thread handling parts is such as to cause the thread clamp to grip the threads at the time the thread pull-off finger 71 is acting on the thread to draw from the supply. Simultaneously with this action, the thread take-up 74 is acting on the thread leading back from the loopers as they move backward and gives thread as they move forward at the point where the loopers have entered the needle loops and additional thread is required as the loopers go forward for the succeeding stitches, at which time the thread grip has released the threads, the finger 71 and take-up 74 giving up the thread as required by the length of stitch being produced.

The operation of the looper mechanism is as follows: As the main shaft 6 rotates in its bearings, the gear 48 transmits motion to the gear 47 and the ball stud 44 which reciprocates the rod 41 and the looper carrier 31, rocking it on the conical studs 30 into and out of the needle loops. At the same time the eccentric cam 16 on the same main shaft 6 is also rotated, giving movement to the block 17 operating in the fork 20 and reciprocating the slide 21 in its way 23, extending across the bed of the machine at right angles to the main shaft 6, or substantially so, (as it is obvious that the groove in the bed of the machine may be at a slight angle with respect to the main shaft, the ball joints provided for connection at each end of the rod 41 and the block 17 being shaped to suit). The angular portion of the fork 20 gives movement to the loopers from the front to the rear of the needles as they are rocking to and fro on the conical studs 30. The mechanism described is for making chain-stitches of the well known two-thread

type, yet it is obvious that other loopers with a slightly different blade may be provided for making the single chain-stitch, such as shown in Fig. 10, or as shown in Fig. 11, in which a tandem looper device is shown. In this style of tandem looper, each looper or each pair of loopers may operate with one or more needles to form the various kinds of well known stitches. In this form of looper the sliding block 21 has pivotally connected to it one or more sets of looper carriers in the form of links 100, according to the number of loopers to be carried, the upper ends of which are linked together as at 101 and support upstanding inclined looper carriers 102, to each of which a looper is adjustably connected in a similar manner to that hereinbefore described. To these linkage connections the pitman rod 41 hereinbefore referred to is adjustably connected, whereby the loopers, one or more pairs thereof, are shifted into and out of the loops during the movement of the slide from one side to the other of the needles. The lower connections of the links 100 may be set the required distance apart so that the loopers may be interchangeable and may be used with various arrangements of needles, and by this means very wide twin needle stitches can be obtained. If an eccentric such as shown in Fig. 7 be used with the block 17 the looper movement from front to rear of the needle will be continuous, while if a cam such as shown in Fig. 9 be employed the looper movement from front to rear of the needles will have a dwell at each side thereof. Such a movement is of advantage where each looper must coöperate with two or more needles in the formation of ornamental stitches, as it permits the looper blades to operate parallel to such needles while taking and leaving the needle loops.

The looper blades are provided with the usual thread eyes and grooves 87 to carry the threads which pass through the thread eyes 89 and the arms 72, 75 and 77 directly to the supply.

It will be seen from the drawings that the location of the looper mechanism, and especially the mechanism for handling the thread, is accessible from the front of the machine without removing covers or guards, yet the thread is entirely out of the way so as not to be interfered with by the handling of the goods and has a direct line of travel, is easily adjusted, and other advantages will be obvious. The looper mechanism is so located as to give ample space for the various devices such as feeding, trimming, ruffling and other devices. The organization of parts for operating the loopers is not confined to a stitch mechanism for making the single or double chain-stitches, but may be employed with equal facility for other types of stitching mechanisms.

From the foregoing it will be observed that in the present improved form of looper mechanism various arrangements of loopers may be used; that is to say, either a single looper such as shown in Fig. 10, or a pair of loopers such as shown in Fig. 5, or, by merely substituting one form of sliding block for another, a tandem arrangement of loopers may be used as occasion may require, and that furthermore, in the present improvement a looper shaft carrying the loopers is entirely dispensed with, the loopers being carried by a sliding block, which facilitates the use of the various arrangements of loopers hereinbefore described.

In conclusion, it will be observed that the means for handling the looper thread enables such threads to be handled from the front of the machine, thus obviating the necessity of such threads passing over the main shaft and also very much facilitating the threading of the parts as well as rendering the thread handling means more accessible.

From the foregoing it will be understood that the various details may be more or less changed without departing from the spirit and scope of this improvement.

By means of this improved looper mechanism either looper may coöperate with two needles so as to make what is known as the twin needle stitch, passing the looper thread from one needle to the other on the bottom of the work by using four needles, two in conjunction with each looper, two rows of twin needle covering stitches may be made at the same time of various widths between the respective needles. Then again, these needles may be set very close together, such as vamping or tip stitching shoes, where the needles are say one-sixteenth of an inch apart but spaced a quarter of an inch or thereabout between the respective twin needles. When the machine is used for making these ornamental or twin needle covering stitches, one needle is set higher than the other according to the space. On the other hand when the machine is used for making separate rows of single needle stitching the needles are set at the same height and the loopers are spaced in accordance with the width between the needles.

I claim as my invention:

1. In a sewing machine having a base provided with a slideway therein transversely thereof the combination of a driving shaft extending lengthwise of the arm of the machine, looper mechanism comprising a slidingly supported plate mounted in the slideway of the base, one or more loopers carried thereby, and means for shifting said plate transversely relatively to said shaft.

2. In a sewing machine, the combination of a driving shaft extending lengthwise of the arm of the machine, looper mechanism

comprising a slidingly supported plate, one or more loopers carried thereby, means having a part thereof secured to the top side of said plate for shifting said plate transversely relatively to said shaft, and means for shifting said looper or loopers transversely relatively to the movement of said plate.

3. In a sewing machine, the combination of a driving shaft extending lengthwise of the arm of the machine, looper mechanism comprising a slidingly supported plate, one or more loopers carried thereby, said slide plate having secured to its upper side an upstanding, rigid bracket, means carried by said bracket for shifting said plate transversely relatively to said shaft, and means for shifting said looper or loopers transversely relatively to the movement of said plate, both of said shifting means having connection with the driving shaft.

4. In a sewing machine having a base provided with a slideway therein transversely thereof the combination of a driving shaft extending lengthwise of the arm of the machine, looper mechanism comprising a slidingly supported plate mounted in the slideway of the base, one or more loopers carried thereby, said slide plate having secured to its upper side an upstanding rigid bracket, means carried by said bracket for shifting said plate transversely relatively to said shaft, means for shifting said looper or loopers transversely relatively to the movement of said plate, and means for adjusting said loopers relatively to the plate.

5. In a sewing machine, the combination of a driving shaft extending lengthwise of the arm of the machine, looper mechanism comprising a slidingly supported plate, one or more loopers carried thereby, said plate having secured to the top side thereof an upstanding rigid fork, means located in said fork for shifting said plate transversely relatively to said shaft, means for shifting said looper or loopers transversely relatively to the movement of said plate, both of said shifting means having connection with the driving shaft, and means for adjusting said loopers relatively to the plate.

6. Looper mechanism for a sewing machine, comprising a slidingly supported plate, one or more loopers pivotally carried thereby, means for operating said plate, means for rocking said looper or loopers relatively to the slide plate, said rocking means including gears, and means for adjusting one of said gears relatively to the other.

7. In a sewing machine, the combination of a driving shaft, looper mechanism comprising a slidingly supported plate shiftable transversely to said shaft, one or more loopers pivotally carried by said plate, eccentric mechanism connected with the driving shaft for shifting the plate, means including gears

one connected with the driving shaft for rocking said looper or loopers relatively to the plate, and means for adjusting the looper or loopers relatively to the plate.

5 8. In a sewing machine having a base provided with a slideway formed therein the combination of a driving shaft extending lengthwise of the arm of the machine, looper mechanism comprising a slide plate located 70
10 in the slideway of the base and having a fork secured to the top side thereof, means carried by said driving shaft and located in said fork for shifting said plate at right angles to the driving shaft, and means also 75
15 connected with the driving shaft for shifting the looper or loopers of the looper mechanism in the same direction as the driving shaft extends.

9. In a sewing machine, the combination 20 of a driving shaft, feed mechanism operatively connected therewith for movement thereby, looper mechanism comprising a slidingly supported plate, one or more loopers pivotally carried thereby, mechanism 80
25 connected with the driving shaft for shifting the plate transversely to the driving shaft, and gears one connected with the shaft for rocking the looper or loopers relatively 85
30 to the plate.

10. Looper mechanism for a sewing machine, comprising a slide, one or more loopers carried thereby, and means for shifting said slide and including means for imparting a dwell thereto at a certain time in its 90
35 shiftable movement.

11. Looper mechanism for a sewing machine, comprising a slide plate one or more loopers carried thereby, means for shifting said slide plate and means for shifting said 95
40 looper or loopers relatively to the slide, one of said means including means for imparting a dwell to the looper or loopers during a certain time in the movement thereof.

12. Looper mechanism for a sewing machine, comprising a slide, one or more loopers carried thereby, and means for shifting said slide and including means for imparting a dwell thereto at each side of the needle. 100

13. Looper mechanism for a sewing machine, comprising a dovetail slide, one or more loopers carried thereby, means for shifting said slide, and means for shifting said looper or loopers relatively to the slide, one of said means including means for imparting a dwell to the looper or loopers at each side of the needle. 105

14. Looper mechanism for a sewing machine, comprising one or more loopers, a sliding plate for supporting said looper or loopers, means for shifting said sliding plate in one direction, and means for shifting said looper or loopers relatively to said sliding plate, one of said means including means for imparting a dwell to said looper or loopers 110
60 at a certain time. 115

15. In a sewing machine, the combination of a driving shaft extending lengthwise of the arm of the machine, looper mechanism comprising one or more loopers located sideways to said driving shaft, means for shifting said looper or loopers sideways relatively to said driving shaft, and means for shifting said looper or loopers in the direction of the length of the driving shaft, one of said shifting means including a slide plate having 70
75 means secured to the top side thereof for the reception of an eccentric carried by said driving shaft.

16. In a sewing machine, the combination of a driving shaft, looper mechanism comprising one or more loopers located sideways to said driving shaft, means for shifting said looper or loopers sideways relatively to said driving shaft, means for shifting said 80
85 looper or loopers in the direction of the length of the driving shaft, one of said shifting means including a slide plate and eccentric mechanism carried by the driving shaft and co-operating directly with a rigid part secured to the top of said slide plate for 90
95 operating said slide plate and the other of said shifting means comprising gearing partly carried by said driving shaft.

17. Looper mechanism comprising a slide plate, and a plurality of loopers link-connected to said plate to swing transversely of the plate in a vertical plane. 95

18. Looper mechanism comprising supporting means and a plurality of aligned sets of link-connected loopers carried thereby. 100

19. Looper mechanism comprising a slidingly supported plate having on its upper side means adapted to co-operate with shifting means for the plate and one or more loopers connected to the upper side of the 105
110 plate for movement transversely of the plate in a vertical plane.

20. Looper mechanism comprising a slidingly supported plate and a plurality of loopers located one behind another and pivotally carried by said plate for swinging movement in a vertical plane. 110

21. Looper mechanism comprising sliding supporting means and a plurality of sets of link-connected loopers carried thereby. 115

22. Looper mechanism comprising a slidingly supported plate, one or more loopers pivotally secured to the top thereof for swinging movement in a vertical plane transversely of the plate, and means for adjusting said looper or loopers relatively to its 120
125 pivotal supporting means.

23. Looper mechanism comprising sliding supporting means and a plurality of aligned sets of adjustable loopers carried thereby. 125

24. Looper mechanism comprising sliding supporting means and a plurality of aligned sets of adjustable link-connected loopers carried thereby. 130

25. Looper mechanism comprising slid-
ingly supported means and loopers carried
thereby and located one behind the other in
alinement.
- 5 26. Looper mechanism comprising slid-
ingly supported means and loopers adjust-
ably carried thereby one looper behind
the other for swinging movement transversely
of said sliding means in a vertical plane.
- 10 27. Looper mechanism comprising sliding
supporting means, one or more loopers, a
link connecting each looper with said sup-
porting means for swinging movement
transversely of said sliding means in a ver-
tical plane.
- 15 28. Looper mechanism comprising sliding
supporting means and a plurality of loopers
linked thereto and pivotally linked to each
other.
- 20 29. Looper mechanism comprising sliding
supporting means, a plurality of loopers
linked thereto and pivotally linked to each
other, and means for adjusting said loopers
relatively to said supporting means.
- 25 30. In a sewing machine, the combination
of a driving shaft extending lengthwise of
the arm of the machine, looper mechanism
comprising a slide plate, one or more loopers
carried thereby, means connected with the
30 driving shaft for shifting the slide plate
transversely to the driving shaft, means
connected with the driving shaft for shift-
ing said looper or loopers relatively to the
slide plate, and means operated by the driv-
ing shaft for controlling and regulating the
35 threads of the looper or loopers.
31. Looper mechanism for a sewing ma-
chine, comprising sliding supporting means,
one or more looper carriers pivotally sup-
40 ported thereon for swinging movement in
a vertical plane relatively to said sliding
supporting means, and one or more loopers
connected with each of said carriers.
- 45 32. Looper mechanism for a sewing ma-
chine, comprising sliding supporting means,
one or more looper carriers pivotally sup-
ported thereon for swinging movement in a
vertical plane relatively to said sliding sup-
50 porting means, one or more loopers connect-
ed with each of said carriers, and means for
adjustably connecting each of said loopers
with its carrier.
- 55 33. Looper mechanism for a sewing ma-
chine, comprising sliding supporting means,
one or more looper carriers pivotally sup-
ported thereon for swinging movement in
a vertical plane relatively to said sliding
supporting means, one or more loopers con-
60 nected with each of said carriers, and means
for adjustably connecting each of said loopers
with its carrier and including one or
more elongated slots carried by each looper.
- 65 34. Looper mechanism for a sewing ma-
chine, comprising sliding supporting means,
one or more looper carriers pivotally con-
- nnected to the top thereof for swinging move-
ment in a vertical plane transversely of said
sliding supporting means, and one or more
loopers connected with each of said carriers.
35. Looper mechanism comprising sliding
supporting means, a plurality of looper car-
riers located one behind another and pivot-
ally connected to said sliding supporting
means for swinging movement in a vertical
plane transversely of said sliding support-
ing means, and a looper carried by each of
said swinging carriers.
- 70 36. Looper mechanism comprising sliding
supporting means, a plurality of looper car-
riers located one behind another and piv-
otally connected to said sliding supporting
means for swinging movement in a vertical
plane transversely of said sliding support-
ing means, a looper carried by each of said
swinging carriers, and means for adjust-
80 ably connecting each of said loopers rela-
tively to its carrier and including elon-
gated slots carried by each looper.
- 85 37. Looper mechanism comprising shift-
able supporting means, a looper carrier
shiftably supported thereon, one or more
loopers adjustably connected with said
looper carrier, and means for adjusting
each of said loopers and including one or
more elongated slots carried by one of said
parts.
- 90 38. Looper mechanism comprising a sup-
porting slide, a looper carrier pivotally con-
nected thereto, one or more loopers adjust-
ably connected to said carrier, and means
100 for adjusting each of said loopers and in-
cluding one or more elongated slots carried
by one of said parts.
- 95 39. Looper mechanism comprising a slid-
ing member, a pair of looper carriers com-
prising links pivotally connected to said
sliding member and linked together, and a
pair of loopers connected with said links
105 for movement in a vertical plane trans-
versely of said sliding member.
- 110 40. Looper mechanism comprising a slid-
ing member, a pair of looper carriers com-
prising links pivotally connected to said
sliding member and linked together, a pair
115 of loopers connected with said links for
movement in a vertical plane transversely of
said sliding member, and means for adjust-
ing said loopers relatively to the sliding
member.
- 120 41. Looper mechanism comprising a slid-
ing member, a pair of looper carriers com-
prising links pivotally connected to said
sliding member and linked together, a pair
125 of loopers connected with said links for
movement in a vertical plane transversely of
said sliding member, and means for adjust-
ing said loopers relatively to the sliding
member and including one or more elon-
gated slots carried by one of said parts.
- 130 42. Looper mechanism for a sewing ma-

chine, comprising a slidingly supported plate, one or more loopers carried thereby, means for shifting said slide, means for shifting the looper or loopers relatively to the slide and comprising a shaft, a gear carried thereby, a gear in mesh therewith, and means for shifting one of said gears toward and from the other.

43. In a sewing machine, the combination of a driving shaft, looper mechanism comprising a slidingly supported plate, one or more loopers carried thereby, means connected with the driving shaft for operating the plate transversely to the driving shaft, means connected with the driving shaft for shifting the looper or loopers relatively to the plate, thread handling means located at the forward side of the driving shaft, and means connected with the driving shaft for operating said thread handling means.

44. In a sewing machine, the combination of a driving shaft, feeding mechanism, looper mechanism, thread handling means located at the forward side of the driving shaft and comprising a shiftable pull-off finger, a shiftable take-up finger, a shiftable nipper plate, means connected with the driving shaft for operating said parts, and means coöperating with said members.

45. In a sewing machine, the combination of a driving shaft, looper mechanism, feed mechanism, thread handling means comprising a rock shaft located at the forward side of the driving shaft, a thread pull-off finger carried by said rock shaft, a thread take-up finger carried by said rock shaft, a nipper plate carried by said rock shaft, means connecting said rock shaft with said driving shaft for rocking the former and the nipper plate, and means coöperating with said shiftable parts.

46. In a sewing machine, the combination of a driving shaft extending lengthwise of the arm of the machine, an eccentric thereon, looper mechanism comprising a slidingly supported plate, a fork secured to the top thereof for the reception of said eccentric, and one or more loopers carried by said slide plate.

47. In a sewing machine, the combination of a driving shaft extending lengthwise of the arm of the machine, an eccentric thereon, looper mechanism comprising a slidingly supported plate, a fork secured to the top thereof for the reception of said eccentric, one or more loopers carried by said slide plate, said looper or loopers also having a movement transversely of the direction of movement of the slide plate, and means for imparting such movement to the loopers.

48. In a sewing machine, the combination

of a driving shaft extending lengthwise of the arm of the machine, an eccentric thereon, looper mechanism comprising a slidingly supported plate, a fork carried thereby for the reception of said eccentric, one or more loopers carried by said slide plate, said looper or loopers also having a movement in a vertical plane, and means for imparting such movement to the loopers.

49. Looper mechanism comprising a slide plate, one or more loopers carried thereby, and a fork secured to the top of said plate for the reception of the means for shifting the plate.

50. Looper mechanism comprising a slide plate having a fork for the reception of the means for shifting said plate, and a plurality of link-connected loopers carried by said plate.

51. Looper mechanism comprising a slide plate, a fork carried thereby for the reception of the means for shifting said plate, and a plurality of loopers located one behind another and pivotally carried by said plate for swinging movement.

52. Looper mechanism comprising a slide plate, a fork carried thereby for the reception of the means for shifting said plate, and a plurality of loopers located one behind another and pivotally carried by said plate for swinging movement in a vertical plane.

53. Looper mechanism for a sewing machine, comprising a sliding plate, a fork on top of said plate for the reception of the means for sliding said plate, a looper carrier pivotally secured to the top of said plate with its pivotal axis extending in the direction of the length of said plate, and one or more loopers carried by said looper carrier.

54. Looper mechanism for a sewing machine, comprising a sliding plate, a fork carried on top of said plate for the reception of the means for sliding said plate, a looper carrier pivotally secured to the top of said plate with its pivotal axis extending in the direction of the length of said plate, one or more loopers carried by said looper carrier, and means for adjusting each of said loopers relatively to said carrier.

55. Looper mechanism comprising a slide plate, a looper carrier pivoted to the top of said plate for swinging movement transversely of the movement of said plate and having a horizontally located pivotal axis, and one or more loopers carried by said carrier.

Signed at Nyack, in the county of Rockland and State of New York, this 3rd day of July, 1915.

JOHN P. WEIS.
